DAM STRUCTURE

Percy E. Hunter and Louis E. Endsley, Pittsburgh, Pa.; said Endsley assignor to said Hunter

Application April 16, 1931. Serial No. 530,460

2 Claims. (Cl. 61—25)

Our invention relates to dams for use in holding back the water of streams and the like, and more particularly to movable dams.

It occasionally happens that temporary dams are required for establishing or maintaining a pool or water level at a given height, and it also frequently happens that dams of the usual fixed type become damaged, so that the pool of water is released. Thus, for example, in the case of 5 navigable streams, the wickets or other dam elements of a more or less permanent nature become broken or displaced, which, of course, results in the lowering of the navigation pool, and prevents movement of steam boats, until after 10 the damage is repaired and sufficient water again accumulated in the pool. Even if the break is discovered immediately, the time required to make the repairs is such that the pool level has fallen to a low point before the repairs are completed. 15 Furthermore, it may happen that the damage is such as to preclude the possibility of making ordinary repairs until the water of the pool has been brought to a low level.

One object of our invention is to provide a 20 dam structure that may be readily rendered buoyant or caused to sink, to facilitate the manipulation of the same.

Still another object of our invention is to provide a dam structure of such form that it 25 may be easily and quickly manipulated and transported without the necessity of employing additional equipment such as tug boats, hoisting devices, etc.

One of the forms which our invention may take 30 is shown in the accompanying drawings wherein Figure 1 is a schematic plan view showing one manner in which our apparatus may be employed; Fig. 2 is a vertical sectional view, on an enlarged scale, through a permanent dam, showing 35 our movable dam structure in end elevation; Fig. 3 is a plan view of the structure of Fig. 2; Fig. 4 is a diagrammatic view showing various floating positions of the movable dam device at 40 various water levels; Fig. 5 is a cross sectional view, on an enlarged scale, through our movable dam structure, and Fig. 6 is a fragmentary plan view thereof.

While the invention is herein shown as employed in connection with permanent dam structures, to prevent flow of water through certain sections thereof, as when breaks occur through damage to the wickets, etc., or for the purpose of facilitating the repairing or placing of wickets or other dam elements, it will be understood that 45 the floating dam structure as herein described can

be employed as a complete dam in itself, where abutments are provided for supporting the ends of the dam.

Figure 1 is a schematic view showing a dam structure such as is commonly employed in 60 navigable streams, the lock being designated by the numeral 8, the various dam sections by the numerals 9, and the piers by the numerals 10. Wickets 11 are shown as included in some of the 65 dam sections 9. Our floating dam is indicated by the numeral 12, and is shown in Fig. 1, as being positioned against two of the piers 10, at which position it may be sunk from its full-line position of Fig. 2, to its dotted line position, to thus prevent flow of water from the pool above 70 the dam, between the piers 10, the arrow in Fig. 1 indicating the direction of stream flow.

Briefly, the floating dam 12 is of barge-like form so that it can be floated from place to place, and can be sunk in an inclined position, 75 as shown in Fig. 2, to hold back the water.

The barge 12 is provided with a buffer 13 adjacent to each end thereof for cushioning the impact of the barge against the piers, the buffers being backed by springs (not shown) after the 80 manner of railway draft gears and the like, or cushioned in any other suitable manner. The buffers 13 are of nose-like form at their outer ends so that they may inter-engage with depressions in the face of the piers 10, as shown more 85 clearly in Figs. 2 and 4, and thus assist in alining the barge with respect to the piers.

The barge is shown as having an inclined bottom wall 14, side walls 15 and 16, and end walls 17. A beam 18 extends from end to end of the barge and serves to stiffen the same, the beam being secured to the bottom and the ends of the barge. Transversely-extending castings or beam-like members 19 and 20 are secured to the sides 90 of the barge and the beam 18 at suitable intervals, to provide the necessary rigidity. A weighted bar 21 of concrete or other suitable material is positioned in one side of the barge to normally maintain the top of the barge in a more or less 95 level position and to serve generally as ballast for the barge. The beam 18 serves also as a partition to divide the barge into front and rear compartments. A water chamber 22 is positioned in the forward compartment of the vessel and has a drain pipe 23 leading to the rear compartment, such pipe being controlled by a valve 24 that is operated through a shaft 25 from the deck of the barge. A series of these drain pipes 23 can be provided, if desired.

A pontoon chamber 26 is provided in the rear 110

compartment of the barge, it being supported therein by the castings 19. A drain pipe 27 leads from the chamber 26 to the exterior of the barge, and is controlled by a valve 28 that may be operated through a shaft 29 from the deck of the barge. An air pipe 30 communicates with the top of the chamber 26, and air under pressure may be supplied therethrough from a compressor 31 to expel water from the chamber 26, as hereinafter explained. A pipe 32 extends from the bottom of the barge to a suction pump 33, whereby water contained within the rear compartment of the vessel may be drawn therefrom. A suction pipe 34 extends to the bottom of the front compartment, so that water may be withdrawn from there also by the suction pump 33.

A deck house 35 is mounted on the barge, for enclosing the power mechanism. The motive power may be in the form of an internal combustion engine, steam engine, or the like. A drive shaft 36 (Fig. 5) operates through bevel gear wheels 37, and drives a vertical shaft 38 that has driving connection with a shaft 39 that in turn drives a shaft 40 that extends longitudinally of the barge and carries at its ends propellers 41, whereby the barge may be moved endwise under its own power.

A pair of drive shafts 42 each operates through associated shafts 43 and 44 to drive a propeller 45 at the rear side of the boat, one of these propellers 45 being located near each end of the barge.

In positioning the barge or propelling the same, either or both of the propellers 45 may be driven, and they may be driven in opposite directions, if desired. The propellers 41 may be driven in either direction, but no provision need be made for simultaneously driving them in opposite directions.

40 The greater depth at the rear of the barge gives it greater buoyancy at that side, tending to raise that portion of it out of the water, and to dip its nose portion into the water. The concrete slab 21 counteracts this tendency, and the barge is so designed that with the chamber 22 filled with water, the barge will float in substantially the position shown in Fig. 2. Upon opening the valve 24, water will flow from the chamber 22 to the rear compartment of the barge, thereby causing the barge to move toward its full-line position in Fig. 4. The valve 28 can also be opened to admit water from outside of the barge into the chamber 26. As the rear side of the barge continues to sink, water can flow over the upper edge thereof into the rear compartment, and the barge will continue to sink until it engages the bed of the stream and its bottom lies against the inclined walls of two adjacent piers, as shown by dotted lines in Fig. 2.

60 It will be understood that the shifting of weight

within the barge preliminary to sinking the same, by opening the valve 24, permits the nose 13 of the buffer member to be brought to such height that it will properly engage the notches in the piers 10.

80 With the barge sunk to the position indicated by dotted lines in Fig. 2, flow between the piers 10 is prevented and a pool level maintained or established.

85 When it is desired to raise the barge and remove the same from the piers, air pressure is supplied through the pipe 30, to force the water out of the chamber 26, so that such chamber will function as a pontoon to raise the barge. Simultaneously with this operation, water may be pumped through the pipe 34 from the front compartment, and through the pipe 32 from the rear compartment, as soon as the upper edge of the barge moves above the surface of the pool. When the water has been expelled from the chamber 26, the valve 28 will, of course, be closed, through manipulation of the shaft 29.

90 The power elements within the deck house 35 are located at such height that they will always be above the stream level even when the barge is sunk at its rear side. Should there be a tendency for the front side of the barge to sink, when the chamber 22 contains water, such portion of the barge can be given greater buoyancy by supplying air under pressure to the chamber 21 through a pipe 47 to displace the water within said chamber.

95 Rapid positioning of the barge may be effected by shifting the center of gravity as it approaches the piers, through admitting water to the rear compartment of the barge as above-explained, to bring it toward its lower dotted line positions of Fig. 4. The force of the stream will immediately move it to its fully operative position as shown in dotted lines in Fig. 2, as soon as the noses 13 engage the piers.

100 We claim as our invention:—

1. The method of controlling flow of water between two pier-like members having their upstream sides inclined upwardly and forwardly from the bed of a stream, which comprises floating a barge-like device into position against the upper sides of said members and sinking the same by tilting movement to cause it to lie against the said inclined sides and prevent flow of water between the piers.

110 2. The method of controlling water through a channel which comprises floating a dam-like element toward a stop member, varying the buoyancy of the front side of said device, to engage the stop member at desired heights, and sinking the rear side of said device while the front side thereof is supported by said stop.
